Primary Examiner — Derrick E Holland*Assistant Examiner* — Janice Patyk(74) *Attorney, Agent, or Firm* — Knobbe Martens Olson & Bear, LLP**CLAIM**

The ornamental design for a bottle, as shown and described.

DESCRIPTION

FIG. 1 is a left, front, and top perspective view of embodiment one of a bottle, showing my new design;

FIG. 2 is a top plan view of the bottle of FIG. 1;

FIG. 3 is a bottom plan view of the bottle of FIG. 1;

FIG. 4 is a front elevational view of the bottle of FIG. 1;

FIG. 5 is a back elevational view of the bottle of FIG. 1;

FIG. 6 is a right elevational view of the bottle of FIG. 1; and

FIG. 7 is a left elevational view of the bottle of FIG. 1;

FIG. 8 is a left, front, and top perspective view of embodiment two of a bottle, showing my new design;

FIG. 9 is a top plan view of the bottle of FIG. 8;

FIG. 10 is a bottom plan view of the bottle of FIG. 8;

FIG. 11 is a front elevational view of the bottle of FIG. 8;

FIG. 12 is a back elevational view of the bottle of FIG. 8;

FIG. 13 is a right elevational view of the bottle of FIG. 8; and,

FIG. 14 is a left elevational view of the bottle of FIG. 8.

The broken lines in the figures illustrate the portions of the design that form no part of the claimed design.

1 Claim, 14 Drawing Sheets(56)
